US0D1106149S

(12) **United States Design Patent** (10) Patent No.: **US D1,106,149 S**
(45) Date of Patent: ** *Dec. 16, 2025

(54) **SMART WATCH**

- (71) Applicant: **Samsung Electronics Co., Ltd.**, Suwon-si (KR)
- (72) Inventor: **Jinwook Kim**, Suwon-si (KR)
- (73) Assignee: **SAMSUNG ELECTRONICS CO., LTD.**, Suwon-si (KR)
- (*) Notice: This patent is subject to a terminal disclaimer.
- (**) Term: **15 Years**
- (21) Appl. No.: **29/929,912**
- (22) Filed: **Feb. 26, 2024**

Related U.S. Application Data

- (63) Continuation of application No. 29/855,801, filed on Oct. 7, 2022, now Pat. No. Des. 1,029,826.

(30) **Foreign Application Priority Data**

- Jul. 7, 2022 (KR) 30-2022-0027366
- (51) LOC (15) Cl. **14-02**

(57) **CLAIM**

The ornamental design for a smart watch, as shown and described.

DESCRIPTION

FIG. 1 is a front perspective view of a smart watch showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The dashed broken lines in the figures depict portions of the smart watch that form no part of the claimed design.
